UNITED STATES PATENT OFFICE.

JOHN W. CLOUD AND AXEL VOGT, OF ALTOONA, PENNSYLVANIA.

MOTOR.

SPECIFICATION forming part of Letters Patent No. 322,794, dated July 21, 1885.

Application filed December 9, 1884. (No model.)

To all whom it may concern:

Be it known that we, JOHN W. CLOUD, a citizen of the United States, residing in the city of Altoona, in the county of Blair and State of Pennsylvania, and AXEL VOGT, a subject of the King of Sweden, but residing in said city of Altoona, have invented certain new and useful Improvements in Motors, of which the following is a specification.

Our invention is specially intended for use in industries requiring little power, sometimes designated as the "small industries;" and it relates to a machine the movement of which is produced by the pressure of a fluid and by the action of gravity exerted upon parts of the machine, as hereinafter specified.

In carrying out our invention we use a casing or wheel, inclosing cylinders, to the piston of each of which is attached a weight free to move with said piston relatively to the casing or wheel, all being mounted so as to be free to rotate together. We also use a valve so constructed and arranged that the rotation of the casing or wheel and its adjuncts will bring certain ports into such relative position as to properly admit the fluid to one cylinder to lift its piston and attached weight, and to allow fluid to escape from the other cylinder to the atmosphere, the whole being so timed as to cause the casing or wheel to revolve by the action of gravity when the center of gravity of the whole mass is at one side of the vertical plane through the axial shaft. We do not restrict ourselves to the number of cylinders and their adjuncts. One cylinder only may be used with a suitable valve, or any suitable number of cylinders. Neither is it essential to our invention that only one valve be used, as a separate valve for each cylinder may be employed.

In the accompanying drawings, Figure 1 is an exterior side elevation of our invention. Fig. 2 is a vertical transverse section. Fig. 3 is a vertical longitudinal section.

Similar letters of reference indicate similar parts in the respective figures.

A is a cylindrically-shaped casing or wheel, free to revolve upon its axial shaft *a*, which is mounted in bearings *B*, provided therefor. The casing *A* is formed in any suitable manner. Preferably one side, *b*, of the casing is

cast integrally with the shaft *a* and adjacent part *b'*, the other side, *b''*, being bolted to the part *b'''*. To the parts *b'* and *b'''* of the casing one or more cylinders, *C*, are attached, each being provided with a piston, *c*. The cylinders are preferably cast solid with the said parts. A weight, *D*, a side elevation of which is shown in Fig. 2, attaches to the end of each piston by means of screw-bolts *f*. The shape in outline of the weight is less than that of a true circle, being that of two united arcs of a circle each having a radius equal to that of the interior of the casing *A*, each arc being less than a semicircle, the construction being such that when the weight rests within the casing, as shown in Fig. 2, a lune-shaped space, *c'*, is left. The center of the weight is cut out or slotted, as shown in Fig. 2, at *c''*, so as to allow it to slide over or upon the cylinders *C*.

The shaft *a* is hollow or tubular, and through it passes longitudinally the valve *g*, which is also tubular. The valve is adjustably attached through the medium of the slotted lug *h* and bolt *h'*, to a bearing, *h''*, secured to a fixed part of the motor. The valve *g*, when so secured, is incapable of rotation. The valve is provided at its longitudinal center with an inclined partition-plate, *i*, an upper supply-port, *i'*, and a lower exhaust-port, *i''*. The supply-port *i'* is adapted to have communication, at the proper time for the admission of fluid to the cylinder occupying the upper position, with a port, *k*, formed in the inner head of said cylinder, while the exhaust-port *i''* is in communication with the port *k* of the other cylinder.

Supposing the position of the ports to be as indicated in Figs. 2 and 3, the fluid is admitted under pressure through the valve *g* to the under side of the piston of the upper cylinder, causing it to rise, and to lift with it the piston of the lower cylinder and the weight *D*. It will be observed that during the time the port *i'* of the valve is in communication with the port *k* of the upper cylinder the exhaust-port *i''* of the valve is opposite the port *k* of the lower cylinder, permitting the fluid to escape from this cylinder. The weight *D* having been shifted from a vertical line, its tendency is to revolve the casing with its contents.

- The effect of the admission and discharge of fluid and the action of gravity, caused by the removal of the center of gravity of the whole mass from a vertical line drawn through 5 the axial shaft, is to cause a continuous rotation of the casing and its contents, and the consequent rotation of the driving-pulley, attached to the shaft of the motor, and from which power is transmitted.
- 10 While this motor is intended to be actuated by an elastic fluid, the same results can be effected by the employment of the force of an explosive compound adapted to be ignited at the proper moment.
- 15 Having described our invention, we claim—
In a fluid-pressure motor, a casing or wheel mounted upon a tubular axis, and a tubular

valve, which does not rotate, passing through the tubular axis, and having a partition-plate and supply and exhaust ports, combined with 20 cylinders within the casing, each provided with a weighted piston and a port adapted to communicate, at the proper time or times, with the supply and exhaust ports of the tubular valve during the rotation of the casing or 25 wheel around its axis, substantially as set forth.

In testimony whereof we have hereunto set our hands and seals.

JOHN W. CLOUD. [L. S.]
AXEL VOGT. [L. S.]
